CLOSURE

Robert Peter Markstein, Vienna, Austria, and
Irwin I. Lubow, New York, N. Y.

Application November 13, 1951, Serial No. 255,913

2 Claims. (Cl. 222—498)

The present invention relates to a closure and it particularly relates to a combination snap-top, screw-type closure particularly applicable to bottles.

Although the present invention has a broad application to screw-top, snap-type closures of the combination type, it has a specific application to closures for cosmetic, pharmaceutical and liquid condiment containers where it is desired to have the closure readily removable as by a screw or bayonet connection to permit re-filling of the bottle, and where it is also possible, by a simple manipulation, which does not remove the cap from the bottle, to permit dispensing of small quantities of liquid from the bottle in connection with cosmetics, pharmaceuticals, flavoring materials, perfumes, liquid dressing and the like.

It is among the objects of the present invention to provide a simple, inexpensive, durable, readily manufactured screw-cap for cosmetic containers or the like, which may be readily applied to seal the cosmetic container and which at the same time may be readily manipulated, to permit the dispensing of small quantities of the liquid, depending upon the purposes for which the bottle is to be used.

It is a further object of the present invention to provide a combination screw and snap type closure for a bottle, and particularly a cosmetic or pharmaceutical bottle, which will readily permit re-filling of the bottle by unscrewing of the cap and readily permit dispensation of small quantities of the liquid received within the bottle, without the necessity of unscrewing or altogether removing the cap or closure.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory, according to one embodiment of the present invention, to provide a plastic type screw cap which may be readily applied and removed from the bottle by means of a bayonet or screw-type connection.

The upper portion of the container desirably has a swinging hinge connection member which has a snap connection to a simple opening or spout through the top of the screw cap.

This central opening is of such a shape and size that small quantities of the liquid, whether it be a cosmetic, pharmaceutical, dressing or liquid material, may be dispensed by inverting the bottle, removing the screw cap and reciprocating the same.

Desirably, the bottle has a sealing means which will seal the spout or opening of the spout upon complete closure of the cap.

The spout is desirably so arranged that it may snap into a recess in the hinged, upper portion of the screw-type closure to assure complete sealing.

With the foregoing and other objects in view, the in-

2

vention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Fig. 1 is a side perspective view of a bottle or container which may be utilized according to a preferred embodiment of the present invention, showing the main body of the cap screw or otherwise connected to the bottle opening with the cover element removed from the top of the screw cap.

Fig. 2 is a transverse vertical sectional view upon the line 2—2 of Fig. 1, upon a large scale as compared to Fig. 1.

Fig. 3 is a side sectional view of the closure of Fig. 2, as applied to a bottle, showing the upper cap portion in closed position.

Fig. 4 is a side sectional view similar to Fig. 3 of an alternate embodiment of the present invention showing a different form of spring retainer for the spout nipple member.

Fig. 5 is a transverse sectional view upon the line 5—5 of Fig. 4.

Referring to Figs. 1, 2 and 3, there is shown a bottle A which may be of glass or a pliable, plastic material, having a screw cap B with a removable snap cover C.

Referring particularly to Figs. 2 and 3, there is shown a neck 10 for the bottle A with a screw formation 11 on the outside thereof.

This neck 10 is designed to receive the sleeve 12, which may be of a molded, plastic material having an interiorly threaded portion 13.

The outside of the sleeve has the depending apron 14. The lower edge 15 of the apron 14 should terminate a short distance above the top contour 16' of the bottle A.

Desirably, the sleeve 12 has a top, transverse plate member 15 molded integrally therewith and there is inserted against the plate an intermediate element 16.

The intermediate element 16 supports the washer 17, which forms a tight contact with the top face 18 of the screw neck 10.

The screw neck 10 will be jammed against the periphery of the washer 17 to assure a seal.

The element 16 is recessed, as indicated at 25, to form the outstanding flange 26 at the base of the nipple member 27.

The nipple member extends upward and mushrooms as indicated at 28, where it is received inside of the spheroidal head 29 of the male snap member 30. The male snap member 30 has an outstanding flange 31 which is attached to the base 32 of the recess 33 in the top of the cap B.

It will be noted that the washer 17, the intermediate element 16, the nipple 27 and the spheroidal head 30 have the through-passages 34, 35, 36 and 37, through which the liquid in the container A may be spurted upon inversion and reciprocation thereof.

Extending outwardly from one side of the sleeve 12 is the hinge member 45, which has an eye at 46 receiving the pivot pin 47.

The pivot pin 47 extends through the eye 46 and into the clevis jaw members 48 depending from and attached to the snap top C.

The snap top C consists of a molded plate 55 having the projecting forward portions 56, which serve as a finger or hand-manipulating member.

The recess 57 receives a supporting inset plate 58 which holds the female snap member 59 in position.

The female snap member is received in a recess 60 and it has a spheroidal recess member 61. The spheroidal recess member 61 receives the spherical cap or spherical head 30, attached to the lower screw-cap B.

From the edges of the spherical recess 60, extends the loop portions 62 of the coil portions 63 to form a complete, resilient connection positioned within the recess.

The receptacle member 61 will be forced into the recess 60 with the side coil member 63 pressed inwardly by the side walls 64 of said recess, and with the turned-over member 62 pressing against the base of the recess.

Between the jaws of the turned-over members 62 is positioned the seal or gasket 65, which is designed to press down upon and seal the top of the spherical member 30 and its central opening 37.

The resiliency of the spherical insert 30 of the spherical recess 61 is such that upon pressing down the hinged cap C, it will be held firmly down in the position as shown in Fig. 3.

To open, by pressing the finger in the ledge 56, it is possible to elevate the swinging cap C and permit dispensation of small quantities of liquid, through the spherical head 30 of the spout at the top of the closure A.

It is thus apparent that the present applicants have provided a simple, inexpensive, readily applied, durable combination snap and screw cap for liquid-containing bottles, particularly cosmetic and pharmaceutical bottles in which the bottle may be quickly filled by removing the screw cap and the contents thereafter slowly dispersed by snapping up or elevating the hinged cover.

After usage, the hinged cover may be readily replaced by pressing down on the hinged cover C until the spherical recess 61 tightly and resiliently engages the spherical head 30.

In the embodiment of Fig. 4 there is shown a bottle M having the screw cap N and the swinging closure P.

According to this embodiment the bottle M, which may be of plastic or glass, has a top neck portion 75 with an external screw thread 76.

The cap N has an internally threaded sleeve 77 which is received on the threaded neck 75.

The internally threaded sleeve 77 has a top closure plate 78 molded of plastic integrally therewith.

Internally of the recess formed by the neck 77 and the top 78 is the cork disk member 79 and the plastic or sealing disk 80 which are compressed against the top 81 of the neck 75 to form a seal.

The plate 78 has a separate upwardly extending spout 82 which has a central axial opening 83 which communicates through the central openings 84 in the cork disk 79 and the facing disk 80.

The spout 82 has a groove or recess 84 which is de-

signed to engage the legs 85 of the spring members 86.

The spring members 86 are of S shape and their outer legs 87 press against the walls 88 of the recess 89 in the swinging snap cap P.

The cap P has the rearwardly extending members 91 which enclose the projecting portion 91 of the screw cap N.

The pivot pin 92 projects through the members 90 and 91 to form a substantially permanent pivotal connection between the snap cap P and the screw cap N.

The block 92 may be inserted in the portion of the recess 94 after the S springs 86 have been inserted into position in the recess 89.

While there has been herein described a preferred form of the invention, it should be understood that the same may be altered in details and in relative arrangement of parts within the scope of the appended claims.

Having now particularly described and ascertained the nature of the invention, and in what manner the same is

to be performed, what is claimed is:

1. A two-piece, hinged top, plastic cap for the neck and mouth of a bottle serving to permit introduction of liquid material into the bottle and dispensation of liquid material from the bottle through the entire mouth with the entire removal of the cap and also permitting alternative dispensation through a central spout with the main body of the cap in position on the bottle, and the hinged top lifted, said cap having a molded plastic internally threaded inverted cup-shaped screw sleeve with a closed top having

30 a central axial opening, a sleeve projecting upwardly through said central axial opening having an outwardly extending flange inside said closed top and having an upper end projecting above said closed top, a spherical male snap element connected to said upper end having an 35 outwardly extending flange connected to said closed top, a plastic top hinged to the closed top having a central recess, and a resilient hollow spherical female shell held in said recess to receive said male snap element and to hold said plastic hinged top in closed position.

40 2. The cap of claim 1, said hinged top and said closed top being provided with gaskets to seal said male and female elements and said male and female elements being provided with outstanding flanges secured to the cap.
